(57) **CLAIM**

The design of the loose leaf binder end portion, as shown and described.

DESCRIPTION

FIG. 1 is a front view of the loose leaf binder end portion; FIG. 2 is a plan view of the loose leaf binder end portion; FIG. 3 is a bottom view of the loose leaf binder end portion; FIG. 4 is a side view of the loose leaf binder end portion with the lever up and the rings closed; FIG. 5 is a front view of the loose leaf binder end portion with the lever depressed; FIG. 6 is a plan view of the loose leaf binder end portion with the lever depressed; FIG. 7 is a bottom view of the loose leaf binder end portion with the lever depressed; and,

FIG. 8 is a side view of the loose leaf binder end portion with the lever depressed and the rings open.
The broken line showing of the loose leaf binder in FIGS. 1–3 is for illustrative purposes only and forms no part of the claimed design.

The broken line showing of the rings in FIGS. 4 and 8 is for illustrative purposes only and forms no part of the claimed design.
